(57) CLAIM

The ornamental design for a luggage case, as shown and described.

DESCRIPTION

FIG. 1 is a front elevational view of a luggage case showing my new design;

FIG. 2 is a rear elevational view thereof;

FIG. 3 is a left side view thereof;

FIG. 4 is a right side view thereof;

FIG. 5 is a top plan view thereof;

FIG. 6 is a top, front, left side perspective view thereof; and,

FIG. 7 is a top, front, right side perspective view thereof.

The background color is for clearer illustration of the article and does not form part of the claimed design.

1 Claim, 7 Drawing Sheets
